DESIGN FOR A PLIER TYPE FASTENER SETTING DEVICE

Roy E. Peterson, Norwalk, Conn., assignor, by
mesne assignments, to Hotchkiss Realty Cor-
poration, Norwalk, Conn., a corporation of
Delaware

Application December 16, 1946, Serial No. 135,538

Term of patent 7 years

(Cl. D74—1)

To all whom it may concern:

Be it known, that I, Roy E. Peterson, a citizen
of the United States, residing at Norwalk, county
of Fairfield, State of Connecticut, have invented
a new, original, and ornamental Design for Plier
Type Fastener Setting Device, of which the fol-
lowing is a specification, reference being had to
the accompanying drawing, forming part thereof.

In this drawing:

Fig. 1 is a side elevation of a plier type fastener
setting device, showing my new design; and

Fig. 2 is a top plan view thereof.

I claim:

The ornamental design for a plier type fastener
setting device, substantially as shown.

ROY E. PETERSON.
